UNITED STATES PATENT OFFICE.

ROBERT M. GILSON, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING APPARATUS.

Application filed September 3, 1924. Serial No. 735,717.

To all whom it may concern:

Be it known that I, ROBERT M. GILSON, a citizen of the United States, residing at Pittsburgh, in the county of Allegheny and State of Pennsylvania, have invented certain new and useful Improvements in Railway Signaling Apparatus, of which the following is a specification.

My invention relates to railway signaling, and particularly to signaling of the type comprising track circuits.

One feature of my invention is the provision in signaling of this type of means for preventing a false clear indication in the event of momentary failure of a car or train to effectively shunt a track relay.

I will describe two forms of signaling apparatus embodying my invention, and will then point out the novel features thereof in claims.

In the accompanying drawing, Fig. 1 is a diagrammatic view showing one form of signaling apparatus embodying my invention. Fig. 2 is a diagrammatic view showing a modification of the apparatus shown in Fig. 1 and also embodying my invention. Fig. 3 is a view partly diagrammatic, showing one form of relay which may be used with the signaling apparatus shown in Figs. 1 and 2.

Similar reference characters refer to similar parts in each of the several views.

Referring first to Fig. 1, the reference characters 1 and 1^a designate the track rails of a railway along which traffic normally moves in the direction indicated by the arrow. These rails are divided by insulated joints 2 to form a track section A—B.

Located adjacent the exit end of the section A—B is a track transformer T, the secondary 3 of which is connected across the rails of the section. The primary 4 of this transformer is connected with a transmission line L which is constantly supplied with alternating signaling current by a generator E.

Located adjacent the entrance end of the section A—B is a track relay C. This relay C is connected with the track rails through a stick or holding circuit, which circuit passes from the lower track rail 1^a, through wires 5 and 6, front contact 7 of relay C, wires 8 and 9, winding of relay C, wire 10,

to the upper track rail 1. Relay C is provided with a pick-up circuit which passes from the lower track rail 1^a, through wires 5 and 11, back contact 12 of an auxiliary relay D, wires 13 and 9, winding of relay C, and wire 10 to the upper track rail 1. It will be seen, therefore, that the back contact 12 of relay D is in a branch around front contact 7 of relay C, and it will also be seen that when relay C is de-energized it can become energized only when back contact 12 of relay D is closed.

Relay D is provided with a circuit which passes from secondary 17 of a transformer U, through wire 31, front point of contact 32—32^a of track relay C, winding of relay D, and wire 33 to secondary 17 of transformer U. Relay D is energized, therefore, when track relay C is energized, but is de-energized when track relay C becomes de-energized. The primary 18 of transformer U is connected with the transmission line L.

Located adjacent the entrance end of track section A—B is a signal S, which, as here shown, is a light signal comprising two lamps G and R, adapted when lighted to indicate "proceed" and "stop", respectively.

The proceed lamp G is provided with a circuit which passes from the secondary 17 of transformer U, through wire 31, front contact 28—29 of relay D, front contact 34 of track relay C, lamp G, and wire 33 to the secondary 17 of transformer U.

The stop lamp R is provided with a circuit which passes from the secondary 17, through wire 31, back contact 32—32^b of track relay C, stop lamp R, and wire 33 to secondary 17.

The stop lamp R is also provided with a circuit which passes from secondary 17, through wire 31, back contact 28—30 of auxiliary relay D, lamp R, and wire 33 to secondary 17. It will be seen, therefore,

that signal S will indicate proceed only when the front contacts of both relays C and D are closed, and will indicate stop when the back contacts of either relay C or D are closed.

The auxiliary relay D is so constructed as to consume a considerable interval of time between the opening of its back contacts and the closing of its front contacts when the relay becomes energized. Referring to Fig. 3, this relay in the form here

shown comprises a rotor 20 operated by a winding 21. The rotor 20 operates a pinion 22 meshing with a segmental gear 23 pivoted at 23^a and biased by gravity to engage with a fixed stop 26. When the winding 21 is de-energized, the segmental gear 23 occupies the position in which it is shown in the drawing, wherein back contacts 28-30 and 12 are closed due to the action of a knob 25. When winding 21 becomes energized, the pinion 22 will swing the segmental gear 23 upwardly until it engages with a fixed stop 27. As soon as this upward movement of the segmental gear begins, the lower knob 25 will allow the back contacts 28-30 and 12 to open, and just before the segmental gear engages the upper fixed stop 27, the upper knob 24 will cause the front contact 28-29 to close. Obviously, a considerable interval of time elapses between the opening of the back contacts and the closing of the front contact, and this interval may be made any desired value.

Referring again to Fig. 1, when the track section A-B is unoccupied, track relay C is energized and auxiliary relay D is energized, so that signal S indicates proceed. When a car enters track section A-B it will de-energize the track relay C, thereby opening the circuit for the proceed lamp G at front contact 34 and closing the circuit for the stop lamp R at back contact 32-32^a, so that signal S will then indicate stop. Relay D also becomes de-energized and after the interval of time required for segmental gear 23 to reach its lowest position, the back contacts of this relay will become closed. When the car leaves the track section A-B, track relay C will become energized through its pick-up circuit which includes back contact 12 of relay D, and will then remain energized due to its stick or holding circuit which includes contact 7 of relay C. After the interval of time required for the operation of relay D, front contact 28-29 of this relay will become closed, whereupon signal S will change from the stop to the proceed indication.

I will now assume that the track rails of section A-B are covered by sand or rust throughout a stretch indicated by the line 35 in Fig. 1, and that this stretch is of such length that the time consumed by a car traveling at normal speed and passing over this stretch is less than the time required for the front contact of auxiliary relay D to close after the relay becomes energized. When the car enters the stretch 35, track relay C will become energized due to the fact that its pick-up circuit is closed at back contact 12 of relay D, and the closing of front contact 32-32^a of track relay C will close the circuit for relay D. Before the front contact 28-29 of relay D becomes

closed, however, the car leaves the stretch 35 and again shunts relay C, which relay therefore becomes de-energized and again opens the circuit for relay D at contact 32-32^a. During the time that the car was on the stretch 35, front contact 28-29 of relay D did not become closed, and, consequently, the proceed lamp G of signal S did not become lighted. It follows that the picking up of track relay C due to the sanded or rusty stretch 35 will not cause signal S to give a false indication.

I will now assume that the section A-B contains a stretch 36 in which the rails are covered with sand or rust, which stretch 36 is longer than stretch 35 and is of such length that the time consumed by a car passing thereover is greater than the time required for the front contact of auxiliary relay D to close after this relay becomes energized. I will furthermore assume, however, that the stretch 36 contains a short gap 37 in which the rails are clean so that relay C will be shunted while the car is passing over this gap. The sanded or rusty stretch on each side of the gap 37 is of such length that the time consumed by a car traveling thereover at normal speed is less than the time required for the front contact of relay D to close after this relay becomes energized. When the car enters the stretch 36, track relay C will become energized, and so the closing operation of auxiliary relay D will begin. This closing operation will not be completed when the car reaches gap 37. When the car strikes the gap 37 track relay C will become de-energized because back contact 12 of relay D is then open. This de-energization of relay C will de-energize relay D, whereupon relay C will not become energized until back contact 12 of relay D closes. This will, of course, occur at some point in the stretch 36 beyond the gap 37, and when such point is reached the cycle of operations of relays C and D will begin again; that is, relay C will become energized, thereby energizing relay D, but the latter relay will not have time to close its front contact 28-29 before the car passes off of the stretch 36. When the car leaves the stretch 36, track relay C will become de-energized, and will remain de-energized until the car leaves track section A-B. It follows that while the car is passing over the sanded or rusty stretch 36, signal S will not give a false indication because at no time are front contact 28-29 and front contact 34 closed simultaneously.

Referring now to Fig. 2, the signaling apparatus shown in this view is the same as that shown in Fig. 1, except that the track-way signal, which is designated S' in Fig. 2, is of the three-indication type, comprising three lamps G, Y and R, arranged when lighted to indicate "proceed", "caution" and

"stop", respectively. The track relay, which is here designated C', is of the three-position type, comprising a track winding 14 and a local winding 15 constantly energized by the secondary 17 of transformer U. A pole-changer P is interposed between the transmission line and the transformer T for reversing the relative polarity of the current supplied to the track rails by this transformer. This pole-changer may be operated by suitable means, not shown in the drawing. The track winding 14 of track relay C' is controlled in the same manner as the winding 14 of track relay C in Fig. 1. When pole-changer P is in one position and section A—B is unoccupied, relay C' is energized in such direction that contact 34—34^a is closed, so that the proceed lamp G of signal S' is lighted. When pole-changer P is reversed, track relay C' becomes energized in the reverse direction, whereupon contact 34—34^b becomes closed and the caution lamp Y is lighted. When section A—B is occupied, track relay C' is de-energized, so that auxiliary relay D is de-energized, and the stop lamp R of signal S' is then lighted through back contact 28—30 of relay D. It will be noted that relay D is energized whenever track relay C' is energized in either direction, that is, whenever either contact 32—32^a or 32—32^b is closed. It will also be noted that the holding or stick circuit for track relay C' is closed whenever this relay is energized in either direction, that is, whenever contact 7—7^a or contact 7—7^b is closed. Back contact 12 of relay D is connected in a branch around either contact 7—7^a or 7—7^b of relay C'.

The operation of the signaling apparatus shown in Fig. 2, in so far as sanded or rusty stretches of track are concerned, is the same as the operation of the apparatus shown in Fig. 1.

Signaling apparatus embodying my invention is particularly well adapted for use where it is impossible to maintain a continuous shunt on the track relay, such, for example, as on railways using lightweight cars or motor busses and subject to stretches of rusty or sanded rails, etc.

Although I have herein shown and described only two forms of signaling apparatus embodying my invention, it is understood that various changes and modifications may be made therein within the scope of the appended claims without departing from the spirit and scope of my invention.

Having thus described my invention, what I claim is:

1. In combination, a track circuit including a track relay connected with the rails through a front contact thereof, a branch around said front contact including a back contact of a slow-acting relay, a circuit for

said slow-acting relay controlled by a front contact of said track relay, and signaling apparatus controlled by said slow-acting relay.

2. In combination, a track circuit including a track relay connected with the rails through a front contact thereof, a branch around said front contact including a back contact of a slow-acting relay, a circuit for said slow-acting relay controlled by a front contact of said track relay, and signaling apparatus controlled jointly by said track relay and said slow-acting relay.

3. In combination, a section of railway track, a first relay provided with a holding circuit including a front contact thereof, means responsive to the presence of a train in said section for de-energizing said first relay, a pick-up circuit for said first relay including a back contact of a slow-acting relay, a circuit for said slow-acting relay controlled by a front contact of said first relay, and signaling apparatus controlled by said slow-acting relay.

4. In combination, a section of railway track, a first relay provided with a holding circuit including a front contact thereof, means responsive to the presence of a train in said section for de-energizing said first relay, a pick-up circuit for said first relay including a back contact of a slow-acting relay, a circuit for said slow-acting relay controlled by a front contact of said first relay, and signaling apparatus controlled jointly by said first relay and said slow-acting relay.

5. In combination, a track circuit including a track relay connected with the rails through a front contact thereof, an auxiliary relay having a front and a back contact and constructed to consume a considerable interval of time between the opening of the back contact and the closing of the front contact when the relay becomes energized, a branch around said track relay front contact including the back contact of said auxiliary relay, a circuit for said auxiliary relay controlled by a front contact of said track relay, and signaling apparatus controlled by the front contact of said auxiliary relay.

6. In combination, a track circuit including a track relay connected with the rails through a front contact thereof, an auxiliary relay having a front and a back contact and constructed to consume a considerable interval of time between the opening of the back contact and the closing of the front contact when the relay becomes energized, a branch around said track relay front contact including the back contact of said auxiliary relay, a circuit for said auxiliary relay controlled by a front contact of said track relay, and

signaling apparatus controlled jointly by said track relay and the front contact of said auxiliary relay.

7. In combination, a section of railway track, a first relay provided with a holding circuit including a front contact thereof, means responsive to the presence of a train in said section for de-energizing said first relay, an auxiliary relay having a front and a back contact and constructed to consume a considerable interval of time between the opening of the back contact and the closing of the front contact when the relay becomes energized, a pick-up circuit for said first relay including the back contact of said auxiliary relay, a circuit for said auxiliary relay controlled by a front contact of said first relay, and signaling apparatus controlled by the front contact of said auxiliary relay.

8. In combination, a section of railway

track, a first relay provided with a holding circuit including a front contact thereof, means responsive to the presence of a train in said section for de-energizing said first relay, an auxiliary relay having a front and a back contact and constructed to consume a considerable interval of time between the opening of the back contact and the closing of the front contact when the relay becomes energized, a pick-up circuit for said first relay including the back contact of said auxiliary relay, a circuit for said auxiliary relay controlled by a front contact of said first relay, and signaling apparatus controlled jointly by said first relay and the front contact of said auxiliary relay.

In testimony whereof I affix my signature.

ROBERT M. GILSON.
